UNITED STATES PATENT OFFICE.

STANISLAW MIDURA, OF PERTH AMBOY, NEW JERSEY.

KEY FOR BRAKE SHOES AND HANGERS.

Application filed January 26, 1922. Serial No. 531,893.

To all whom it may concern:

Be it known that I, STANISLAW MIDURA, a citizen of the United States of America, residing at Perth Amboy, in the county of Middlesex and State of New Jersey, have invented certain new and useful Improvements in Keys for Brake Shoes and Hangers, of which the following is a specification.

The present invention relates to certain new and useful improvements in keys for securing brake-shoes to the heads of car brakes.

The primary object of this invention is the provision of a key for brake-shoes wherein it will be impossible for the key to become loose and consequently displaced from its operative position.

A further object of the invention is the provision of a spring member rigidly carried by the key, which after the key has been inserted in its position between the brake-head and brake-shoe, the spring will properly function so as to prevent the key from becoming accidentally displaced.

A still further object of this invention is the provision of an improved hanger for the brake-head, whereby the same may be supported in a swinging relation with respect to the beam of the truck frame.

With the above and other objects in view, the invention consists of the novel form, combination and arrangement of parts hereinafter more fully described, shown in the accompanying drawing and claimed.

In the drawing, wherein like reference characters designate corresponding parts throughout the several views,

Figure 1 is a side view partly in section and partly in elevation of a usual form of brake-head and shoe, with the key in its proper position,

Figure 2 is a perspective view of my improved key,

Figure 3 is a similar view of the leaf spring attached to the key, and

Figure 4 is an enlarged detail view, partly in section and partly broken away of the brake-head hanger.

Referring more in detail to the accompanying drawing, 5 indicates any conventional type of brake-head carrying the usual lugs 6 and 7. A standard form of brake-shoe is shown at 8 and likewise carries a lug 9 adapted to be received between the lugs 6 and 7 of the brake-head when the shoe is positioned for operatively connecting with

the brake-head 5. The lugs 6, 7 and 9 have the usual aligned apertures which provide a key-way for the key 10, by means of which the shoe and head are locked together. The shank of the key 10 is suitably tapered so that when the key is driven to the position in which it is shown in Fig. 1 it will draw the shoe 8 into firm contact with the face of the head 5.

The key 10 is provided at a point spaced upwardly from its lower end with an inclined slot 11 adapted to receive one end of a substantially elongated leaf spring member 12. The spring 12 consists of a single piece of spring steel of a width comparatively that of the key 10 and is slightly curved outwardly so that when its lower end is positioned within the key slot 11 the upper end of the spring will be spaced a slight distance away from the adjacent face of the key 10. The slot 11 is incut from the rear surface 10' of the key 10 and has at its lower terminus a substantially circular tapered groove 13 adapted to receive a circular tapered head 14 of the key 12. It will be seen that the slot 11 and groove 13 are transversely of the key 10 and that when the spring 12 is slid transversely within the slot 11 the tapered head 14 of the spring will be firmly wedged within the groove 13 to securely retain the spring within the slot. As a means for positively retaining the spring within the slot, rivets or other fastening means may be provided.

From the foregoing description it will be clearly seen that when the key 10 is being positioned for use between the head 5 and shoe 8 the spring 12 will be forced against the inner face 10' of the key 10 while the same is passing through the aligned apertures of the lugs 6, 7 and 9 carried by the head and shoe. When the spring 12 is completely passed through the aperture in the lower lug 7 of the head 5 the same will spring outwardly so as to impinge against the inner face of the lug 7, consequently preventing the key from being accidentally displaced from its operative position. To remove the key from between the head and shoe all that is necessary is to apply a slight pressure to the spring 12 to aline the same with the apertures in the lugs at which time the key may be readily removed.

As a means for supporting the brake-head 5 upon the truck frame beam 16 there is provided, as clearly shown in Fig. 4, a

2

bracket member 17, comprising a base plate 18 and integral forwardly projecting legs 19. The brake-head 5 is provided with the usual transverse slot 20 adapted to receive the lower integral cross member 21 of two substantially vertical connecting arms 22. The cross member 21 and vertical arms 22 form in reality a substantially U-shaped link for connecting the brake-head 5 to the bracket 17. The upper end of each arm 22 is pivotally secured to the forwardly projecting legs 19 of the bracket 17 by rivets 23 or other pivoting means. The plate 18 of the bracket 17 is rigidly secured, as at 24, to the adjacent side face of the beam 16.

While there is herein shown and described the preferred embodiment of the present invention, it is nevertheless to be understood that minor changes may be made therein without departing from the spirit and scope of the invention.

What is claimed as new is:—

1. In combination with a brake-head and

shoe having interengaging lug members with aligned apertures when the same are positioned together, a wedge shaped key extending through said lug apertures and having an inclined slot cut therein, a spring member with its lower end received within said slot, the upper end of which is adapted to impinge against the inner face of the lower lug of the brake-head for retaining the key in operative position.

2. A key for brake-heads and shoes having an inclined slot adjacent its lower end, the lower terminus of said slot being in the form of a circular tapered groove, a leaf spring having a substantially circular tapered head at its lower end, the said tapered head and a portion of said spring adapted to be received within the inclined slot and tapered circular groove for rigidly maintaining the same therein.

In testimony whereof I affix my signature:

STANISLAW MIDURA.
